UNITED STATES PATENT OFFICE.

MARION L. RIGGS, OF INTERNATIONAL FALLS, MINNESOTA.

HAIR-CLIPPER.

1,354,458.

Specification of Letters Patent. Patented Sept. 28, 1920.

Application filed January 21, 1919. Serial No. 272,298.

To all whom it may concern:

Be it known that I, MARION L. RIGGS, a citizen of the United States, residing at International Falls, in the county of Koochiching and State of Minnesota, have invented new and useful Improvements in Hair-Clippers, of which the following is a specification.

This invention has reference to improvements in hair clipping machines.

In the ordinary construction of hair clipping devices the reciprocatory blade is rigidly secured to the handle, and as a consequence the operator has difficulty in conveniently holding the same during the hair clipping process, inasmuch as the blade must be retained at different angles or inclinations during the operation thereof. The ordinary construction of such devices has the toothed guard thereof in the nature of a flat plate, and consequently the same can not be held in contact with the head of the person operated on, especially when hair is being clipped above the neck, and as a consequence the barber can not accurately cut hair above the neck, this portion of the hair being severed with a scissors. In addition to this, the ordinary construction of hair clipping devices has its cutting blade provided with teeth at only one of its edges and the guard therefor likewise provided with teeth only at one of its edges, so that the depth of the cut would be the same throughout did not the barber hold the device at various angles.

It may be considered the object of the present invention to produce in a single article of this class motor operated means which will overcome all of the foregoing objections and afford other points of superiority and advantages over the ordinary construction of such implements.

It is a still further object of the invention to produce a hair clipping apparatus that shall comprise only a few simple parts easily associated or disassembled, as for repairs or cleaning, one which may be operated in an easy manner and which will materially assist the barber in hair clipping operations.

The foregoing objects may be accomplished by a construction, combination and operative arrangement of parts such as illustrated by the accompanying drawings, in which:

Figure 1 is a top plan view of the improvement;

Fig. 2 is an edge view of the same;

Fig. 3 is a bottom plan view of the same; Fig. 4 is a longitudinal sectional view approximately on the line 4—4 of Fig. 1;

Fig. 5 is a transverse sectional view approximately on the line 5—5 of Fig. 1; and Figs. 6 to 12 illustrate details.

The head of the improvement is indicated by the numeral 15 and the handle therefor by the numeral 16. The handle is pivotally secured to the head as will be presently apparent, and this pivot provides the means for retaining the major elements of the construction associated.

The head includes a guard 17 that comprises a member which has its outer surface rounded both transversely and longitudinally, as indicated by the numeral 18, and has its edges provided with spaced teeth 19 and 20 respectively. The teeth 19, from the outer edge of the guard are cut at an angle providing the outer edges thereof with straight surfaces 21, and these straight surfaces arrange the active and inner edges of the teeth a suitable distance above the outer edges thereof, or the edges formed on the rounded surface 19 of the guard. The guard 17, from the edges of the teeth 19 and 20 are arranged at an inward angle, and the said guard, in a line with the said angle is provided with straight surfaces 22 against which the inclined lower corners of the reciprocating blade 23, inward of the teeth 24 and 25 formed on the said edges, are designed to rest. The guard 17 is dished upon its outer surface and is centrally provided, from its ends with longitudinal slots or channels 26 and with outstanding ribs 27 arranged in a line with the side walls of the channels 26. Both the channels and ribs terminate adjacent to the center of the guard 17, the said center of the guard being provided with a flat substantially rectangular surface 28 which is preferably arranged flush with the outer edges of the ribs 27 and which is centrally provided with a round opening 29. The central portion of the blade 23 rests on the outer edges of the ribs 27, and the channels 26 receive therein lugs 30 formed on the under face of the blade and extending inwardly from adjacent to the ends thereof. The blade, at the center

thereof is provided with a transversely extending elongated slot or opening 31.

The cap or head plate for the head proper is indicated by the numeral 32 and is designed to overlie the blade 23. The cap plate 32 is of a less width than that of the blade and is provided, upon its edges with spaced depending lugs 33 that bear directly on the blade, so that the blade does not contact with the full surface of the cap plate. The cap plate has its ends formed with depending flanges 34 of spring material which normally exerts a pressure or tension toward each other, and each of the flanges has its inner face provided with a substantially rectangular lug 35 of a width to be snugly received between the ribs 27 and in the channels 26 of the guard 17. This holds the cap plate against lateral movement with respect to the head 15, the same being held against longitudinal movement by the frictional engagement of the flanges or sides 34 with the ends of the guard 17. The cap plate is centrally provided with a round opening 36 and is provided with a series of equally spaced apertures 37 arranged concentrically around the opening 36.

The handle 16 is preferably arranged at an angle with respect to the head 15. The handle is constructed of two connected members or sections. The lower section is indicated by the numeral 38 and has its inner end formed with a hollow head portion in the nature of an annulus or ring, the same being indicated by the numeral 39. The annular head 39, at the lower wall thereof is provided with both inturned and outturned flanges 40 and 41 respectively, so that the base of the head is comparatively wide, and this widened surface rests directly on the cap plate 32. The under surface of the annular head 39 is formed with a depending annular flange 42 designed to be received in the round opening 36 of the cap plate 32. The lower section 38 of the handle 15 has pivotally secured between suitable lugs 43 formed thereon a spring influenced dog 44, the active or toothed end of which engaging in one of the apertures 37 of the cap plate 32. The outer face of the section 38 of the handle is hollow and the upper edge or surface thereof is arranged a considerable distance above the upper edge of the annular head 39. The hollow section is provided, at its ends and inward of the said ends with transverse enlargements or partitions 45, each of which having a central alining substantially semi-cylindrical depression 46 arranged longitudinally of the handle section, and these depressions form bearings for shaft members or sections, as will presently be described.

Received in the hollow head 39 and bearing on the inner flange 40 thereof is a round member having its outer surface provided

with peripheral teeth. This gear member is indicated by the numeral 47 and has formed, upon its under or lower face a depending annular round extension arranged off the center of the said gear so as to provide a cam member which is indicated by the numeral 48. The cam member or wheel 48 is adapted to pass through the opening in the cap plate and to be received in the opening 31 of the blade 23 and to contact with the end walls provided by the said opening whereby, when the gear 47 is turned the blade 23 will be reciprocated over the gear 17. The cam, as well as the gear 47 have an opening therethrough which is indicated by the numeral 49.

The outer surface of the handle 16 is indicated by the numeral 50 and is of a substantially similar construction to that of the lower section 38, the inner face of the said outer section being hollow and being provided with transverse connecting members for the sides thereof in the nature of ribs or partitions 51 that are provided with semi-cylindrical depressions 52 arranged transversely of the said partitions in longitudinal alinement with respect to the said handle section. The inner end of the section 50 is provided with a round depending hollow head 52 provided with an opening 54 at its juncture with the handle proper, the said head being wider than the inner end of the handle, and this hollow head is designed to be received over the annular head 39 of the lower section and to rest upon the outer flange 41 of the said lower section. The head 53 is designed to rest directly on the upper edge of the annular head 39 of the lower section 38, the said head 53 being provided with a central opening 55. The handle sections are connected in any desired or preferred manner, preferably through the medium of removable elements, such as headed screws 56 passing through non-threaded openings in the section 50 and engaging the threads in alining openings in the section 38.

In the hollow head 53, and meshing with the toothed gear 47 is a pinion 57 secured upon a shaft 58 that finds a bearing in the inner series of registering semi-cylindrical depressions in the transverse ribs or partitions of the respective handle sections. The shaft may be provided with lugs or collars 59 that contact with one or both of the partitions in which the same find a bearing to hold the said shaft against longitudinal movement. The shaft 58 is comparatively short, being less than one-half the length of the handle 16, and the other end of the said shaft, or the end thereof provided with the pinion 57 is centrally formed with a square socket 60.

Arranged for slidable movement between the inner partitions of the handle 16 is a

clutch member 61 having the end thereof nearest the shaft 58 provided with an annular depression or flange 62 that all times receives the end of the said shaft 58. The clutch 61 is provided with a square or rectangular finger 63 arranged inwardly and centrally of the hollow extension or flange 62, and this finger is designed to be received in the socket 60 when the clutch member is moved longitudinally in the direction of the short shaft. The clutch member is round in cross section and is approximately centrally provided with spaced annular flanges 64 receiving therebetween a sleeve 65 having extending therefrom a finger piece 66 on which is formed laterally extending spaced spring plates 67. The finger passes through an elongated opening in the outer section 50 of the handle 16, the outer spring 20 plate contacting with the outer surface of the said section and closing the opening, the inner plate 67 contacting with the inner surface of the handle section. The opening, for distinction is indicated by the numeral 68, and it will be apparent that by moving the finger piece inward or outward of the handle the clutch member will be moved longitudinally to bring the finger 63 thereof in the socket 60 of the short shaft 58, or out of the said socket. The outer end of the clutch member 61 is centrally provided with a square or rectangular socket 69 receiving a square or rectangular finger 70 formed on the end of a short shaft 71 that finds a bearing in the registering semi-cylindrical depressions in the outer transverse members or partitions formed on the sections of the handle 16. The short shaft 71 is held against longitudinal movement by flanges or collars 72 formed thereon and contacting with the referred to partitions. The outer end of the short shaft 71 passes through an exteriorly threaded bushing 73 formed on the outer end of the handle 16, and the said end of the short shaft is provided with a square or rectangular socket 74. This socket is adapted to be engaged by a pin 75 formed or secured to the inner end of a flexible shaft 76, the casting 77 for the shaft having its end provided with an interiorly threaded revoluble connecting socket 78 designed to threadedly engage with the bushing 73 whereby to connect the flexible shaft 76 with the short shaft 71. The flexible shaft is designed to be hitched or connected to any desirable source of power (not shown).

The guard 17, upon its outer bulged surface is centrally reamed or otherwise provided with a depression 79 that surrounds the opening 29, the said depression receiving the head 80 of a pivot screw 81, the shank of the screw passing through the opening 29 in the guard, the opening 49 in the gear 47 and cam therefor, and passing

through the opening 55 in the head 53, and the threaded end of the said pivot screw or bolt being engaged by a nut 82 that contacts with the head 53 of the handle section 50, and by this means the handle is connected with the head. Preferably the pivot screw or bolt 81 has also arranged thereon a locking nut 83, preferably in the nature of a winged member which binding against the nut 82 holds the same against turning. 75

It is believed, from the foregoing description, when taken in connection with the drawings, that the advantages of the construction will be fully apparent. It will be seen that the head may be arranged at 80 any desired angle with respect to the handle; that the out-bulged surface of the guard permits of the proper tilting of the head 15 to clip hair at a desired angle; that the double toothed blade permits of hair 85 being clipped from either side of the device; that the head 15 may, by the operation of the dog 44 be swung angularly and retained at such angles with respect to the handle, that the clutch means permits of 90 the continuous turning of the flexible shaft when the device is in or out of operation, the peculiar straight formation of the ends of the teeth 19 permits of the guard to rest on the scalp or neck of the person operated 95 on to sever or clip the hair a predetermined length, or in other words the hair will not be cut close to the scalp, and still further that the peculiar outer contour of the guard 17 permits of the same readily adapting 100 itself to the scalp or neck of the person operated on and the tilting of the head of the device either laterally or longitudinally.

Having thus described the invention, what is claimed as new, is:— 105

1. In a hair clipping device, a guard which is of a greater thickness at its longitudinal center than at any other part thereof and which has the outer surface at its center rounded and inclined upwardly to 110 the edges thereof, one of such edges being cut to provide a straight surface, and both of the edges being formed with laterally extending teeth, a blade having its opposite edges provided with teeth resting on the guard and reciprocatory thereover, and means for imparting such motion to the blade, a cap plate overlying the blade, and interengaging means between the ends of the cap plate and the ends of the guard. 115

2. In a hair clipping device, a guard having its outer face bulged to the center thereof and having its edges provided with laterally arranged teeth, a reciprocatory blade having its opposite edges toothed on the inner face of the guard, and means for imparting a reciprocatory movement to the blade, a cap plate arranged over the blade and having spaced lugs which contact with the blade, and spring flanges on the ends of 125 130

the cap plate having elements thereon engaging with and sustaining the cap plate on the guard.

3. In a hair clipping device, the combination with a guard having teeth on the opposite edges thereof, a toothed blade mounted for reciprocation on the guard, a cap plate having spaced lugs contacting with the blade, spring flanges on the ends of the cap plate, interengaging means between the flanges and the ends of the guard, a

pivoted handle having means for imparting a reciprocatory movement to the blade arranged over the cap plate, a spring influenced dog carried by the handle, and said cap plate having spaced concentrically arranged apertures designed to be engaged by the dog for retaining the handle angularly with respect to the guard and cap plate. 15

In testimony whereof I affix my signature. 20

MARION L. RIGGS.
